UNITED STATES PATENT OFFICE.

JAMES H. SHEAHAN, OF FREEPORT, ILLINOIS.

JACK.

1,265,264.

Specification of Letters Patent. Patented May 7, 1918.

Application filed November 13, 1912. Serial No. 731,079.

To all whom it may concern:

Be it known that I, JAMES H. SHEAHAN, a citizen of the United States, residing at Freeport, in the county of Stephenson and State of Illinois, have invented a certain new and useful Improvement in Jacks, of which the following is a specification.

This invention relates to jacks and has for its object to provide a new and improved portable jack adapted to be operated by a suitable motor.

The invention is illustrated in the accompanying drawings, wherein—

Figure 1 is an elevation of a jack embodying the invention with a portion of the outer casing removed showing the internal mechanism;

Fig. 2 is a sectional view taken on line 2—2 of Fig. 1;

Fig. 3 is a view showing one form of motor to be used in operating the jack;

Fig. 4 is a sectional view taken on line 4—4 of Fig. 3;

Fig. 5 is a view showing several jacks in use and arranged so that the load upon them will be equalized automatically;

Fig. 6 is a sectional view taken on line 6—6 of Fig. 2;

Fig. 7 is a view showing the jack mounted on wheels;

Fig. 8 is a view showing a form of beveled teeth for the toothed wheels where the train of gears are disconnected;

Fig. 9 is a view showing the ratchet and brake for the driving shaft;

Fig. 10 is a view showing one construction of the fan on the driving shaft;

Fig. 11 is an enlarged sectional view taken on line 11—11 of Fig. 10;

Fig. 12 is a sectional view taken on line 12—12 of Fig. 1;

Fig. 13 is a side view with parts broken away of a jack having a straight front;

Fig. 14 is a front view of the device shown in Fig. 13.

Like numerals refer to like parts throughout the several figures.

In the construction illustrated in the drawings, I have shown a jack having a casing 1 and a movable lifting member 2 mounted in said casing. Said movable lifting member may have the two load engaging parts 2^a and 2^b and is preferably provided on opposite sides with teeth 3 which are engaged by toothed wheels 4 and 5, the movable lifting member being located between

these toothed wheels so that the power is applied evenly on opposite sides and lateral strain removed. The toothed wheels 4 and 5 are connected to gears 6 and 7, said gears 60 being preferably connected together so as to rotate in unison. The toothed wheels 4 and 5 through the agency of the gear 6 are connected by a train of gears with a shaft 8 so that power applied to said shaft may be 65 multiplied. The shaft 8 is arranged so that a motor or other power applying device may be applied thereto. In the construction shown, this train of gears consists alternately of the small toothed wheels 9 and the 70 large toothed wheels 10, the large wheels meshing with the small wheels. A portion of this train of gears is located on one side of the movable member 2 and the other portion on the other side of said movable member. Connected with this train of gears are one or more intermediate power applying 75 shafts 8^a arranged so that power may be applied along the different points of said train of gears so as to vary the power applied to 80 the movable member at a speed of movement of said member. When power is applied at an intermediate point to the train of gears, said train is disconnected so that the gears at the rear of the point of applying the 85 power will be thrown out of gear and will remain idle. Any desired means may be used for this purpose. In Fig. 6, I have illustrated a simple construction for this purpose. The small toothed wheel 9 is slidably mounted upon the shaft 8^a and is provided with teeth 11 adapted to engage teeth 12 on the gear 10. It will be seen that by sliding the small wheel to one side, it will be disconnected from the next large wheel 10. 90 This sliding to one side may be accomplished by means of a suitable forked controlling member 13 which projects through a slot 14 in the casing of the jack. The teeth of the small gear 9 and large gear 10 where the 95 connection and disconnection are made, are preferably beveled at their ends so that they will be easily connected when the gear 9 is slid toward the gear 10 even when the teeth are not in mesh, the beveled faces moving 100 the gears relatively so that the teeth will mesh. This beveled construction is shown in Fig. 8. It will be seen that this train may be disconnected at any number of intermediate points. I have simply shown one 110 point for purposes of illustration. Any suitable motor may be applied to the shaft.

8 or to the shaft 8^a. I have illustrated in Fig. 3 one form of motor which can be operated by a small amount of power. This motor as illustrated is an air motor. In 5 view of the fact that one of the important uses of these jacks is in connection with railway work, either in railway shops or on wrecking cars or out on the line wherever it is desired to jack up a car or engine, I 10 have shown this motor as an air motor as there is always compressed air handy on the trains or in the shops so that the motor can be easily and quickly coupled up to the source of air supply in the shops or to the 15 air pipe of the train. This motor is also arranged to act as a brake when not acting as a motor thus permitting the movable member 2 of the jack to be gradually lowered when desired. As illustrated in the drawings, 20 the motor is provided with a series of cylinders 15 provided with pistons 16 connected by a connecting rod 17 and cranks 18 to the shaft 19. This shaft is provided at both ends with a shank 20 having a non- 25 circular hole therein, said shank adapted to be slipped over the end of the shaft 8 or 8^a which is also non-circular. Each cylinder is provided with an admission port 21 adapted to be connected to the source of air supply 30 and an exhaust port 22 adapted to exhaust into the atmosphere. Associated with each cylinder is a controlling valve 23 connected with the rotatable shaft 24 to which is connected a wheel 25. A wheel 26 is connected 35 with the shaft 19 and these two wheels are connected together by a suitable belt 27. As air is admitted through the admission port 21, the piston moves downwardly and the valve 23 rotates in the direction of the arrow, 40 keeping the port 22 closed and the port 21 open. When the piston reaches the end of its stroke and is ready for the return stroke, the valve 23 is moved so as to open the exhaust port 22 and close the admission port 21. The piston now moves upwardly 45 forcing the air out of the exhaust port. If now the air is turned off and the weight on the movable member of the jack starts to move said movable member downwardly, the motion of shaft 19 is reversed. This 50 reverses the movement of the valve 23 causing it to move in a direction opposite to the arrow. If now the piston moves downwardly, it will be seen that the valve 23 will 55 be moved in the direction opposite the arrow and will close the admission port 21 and open the exhaust port 22, permitting air to be drawn in. As the movement continues and the piston starts on its upward stroke, 60 the valve 23 moves to a position where it closes the exhaust port 22 and opens the admission port 21. The piston then forces the air through the admission port 21 back to the source of supply of air. The admission 65 port is provided with a pipe 21^a leading to

the source of air supply having a valve 28. By controlling this valve this compressed air may be let out gradually so as to permit the movable member of the jack to lower gradually thereby giving complete control of the 70 backward movement of the jack, the motor acting as a brake to retard this backward movement. I prefer to have three or more cylinders 15, all of them being connected by a pipe 21^a with the same source of air supply. The cranks of the three cylinders will be at different angles so that there will be no dead center. The motor is preferably provided with the projecting handles 29 by means of which it is held in position when 80 connected with the shafts 8 or 8^a. I prefer to provide some means for holding the motor in position without requiring the attendance of the operator. As shown in Fig. 7, the casing of the jack is provided with 85 the lugs 30. When the motor is connected with the shaft 8, a bar 31 is run behind these lugs and one of the handles 29 on the motor engages this bar, thus holding the motor in position. The shank 20 of the motor may be 90 connected with the shaft 8 by means of a removable pin 32, in which event the shank and shaft may both be circular. I prefer to provide both ends of the motor shaft with the shanks 20. When one shank is connected with the shaft 8, the motor drives the movable member of the jack upwardly. If now the weight on the jack is not sufficient to move it back, the motor may be turned around and the other shank 20 placed on the 95 shaft 8 whereupon the motor will reverse the movement of the train of gears and jack and positively lower the movable member 2. In Fig. 5, I have shown a series of jacks arranged so that the load upon them will be 100 automatically equalized. These jacks are shown for purposes of illustration beneath the end of a heavy weight 33 which is to be raised to an inclined position, thus illustrating a condition where the movable members 105 of each of the jacks must be moved a different distance and at a different speed. Under these conditions, the several motors 34 associated with the various jacks are connected by separate pipes 35 with a storage tank 36, 110 said storage tank being connected by pipe 37 with the source of air supply. The pipe 37 is provided with a valve 38 to control the pressure of air in the tank 36. This tank is also preferably provided with a safety valve 115 38^a and has a series of projecting connecting elements 39 to which the pipes 35 are connected. Each of these connecting elements is provided with a suitable valve so that the air passing therethrough may be controlled and 120 so that when not in use may be shut off. It will be seen that by means of this construction, the motor for all the jacks is connected with the same source of air supply and 125 therefore has the same pressure. As the 130

weight upon any movable member of any jack increases, it will be seen that the jack will automatically slow down so as to permit the other jacks to catch up as it were, the result being an automatic equalization of the pressure of the movable members of all of the jacks. It will be seen that by means of this invention any number of jacks may be placed under a given load and yet the pressure on the movable members of the jacks will be automatically equalized without regard to the relative height of the movable members of the several jacks and without requiring operators at the several jacks, as a single operator at the tank can control all of these jacks at will by operating the proper valves. With this construction the load may be lowered by the operator at the tank shutting the valve 38 so as to disconnect the tank from the source of air supply, whereupon the motors of the jacks will be rotated backwardly and will act as brakes forcing the air into the tank 36. The operator may let out this air by means of any of the proper valves so as to secure the proper backward movement of the jacks. This backward movement will also be under equalized pressure. I also prefer to arrange the jacks so that they can be easily moved from place to place. This may be done for example by means of wheels 40 mounted on an axle 41. This axle may be removably connected to the jack in any desired manner as by means of the overhanging lugs 42 and the rotating holding part or button 23. The wheels can be removed by turning the button 43 and then moving the axle out from under the overhanging lugs. When the wheels are in position, the jacks may be inclined so that the weight rests on the wheels and they can then be easily moved from place to place. When an air motor is used to operate the jack it can be arranged to operate with a very low pressure such as ten pounds or less. The jacks can be made of any desired size, capacity, form or arrangement depending upon the conditions under which they are to be used. I have shown a simple form of construction for the purpose of illustration but I do not limit myself to the form and arrangement herein shown.

When the jack is used out on the road, for example, it can be connected to the air hose on the car at or near where the jack is to be operated, thus making it simple, easy and convenient to use. I have shown an air motor for the reason that all shops and trains are provided with air thus making it easy to operate the jack in any of these constructions.

The jack is provided with some suitable means for holding the movable part in any of its various positions. Any suitable arrangement for this purpose may be used. As herein shown, the shafts 8 and 8^a are provided with a ratchet wheel 44, there being a pawl ratchet 45 arranged so that when in engagement with the teeth of the ratchet wheel, the backward movement of the jack will be stopped. When the jack is being used this pawl may be moved out of engagement with the ratchet wheel and moved back into engagement when it is desired to stop the movable member of the jack and hold it in any desired position.

The shafts 8 and 8^a are also preferably provided with a brake wheel 46 there being a braking lever 47 arranged so that it can be moved into engagement with the brake wheel so as to control by hand the backward movement of the jack. The jack itself may be operated by means of a crank or any other hand mechanism by connecting said mechanism with the shaft 8.

I prefer to provide the shaft 8 with a suitable retarding fan 48 so that if the power should fail and the movable member of the jack start downwardly under the load this fan would act to retard the backward movement so as to prevent injury to the parts. It will be seen that if the movable member of the jack moves downwardly under the load the shaft 8 would be moved at a very high rate of speed on account of the gearing and hence the fan would provide a sufficient resistance to prevent injury to the parts. I prefer to arrange this fan so that it provides a smaller resistance as the jack member is moved upwardly and a greater resistance as the jack member is moved downwardly.

I have shown one arrangement for this purpose wherein the fan blades are made V-shape the point of the V moving against the air as the jack member is moved upwardly and the open part of the V moving against the air as the jack member moves downwardly thereby greatly increasing the resistance. It will also be noted that in this particular construction there is no unnecessary friction as the various gears may be mounted in ball bearings in the usual manner.

Some suitable means is provided for automatically stopping the jack when the movable member reaches this upward limit of its movement. As shown in Figs. 1 and 12, the shaft 8 is provided with a brake actuated by the movable member 2 when it reaches a predetermined position. This brake as shown consists of the arms 50 and 51 connected together and properly supported. The member 2 has an engaging part 52 which engages the arm 50 and causes it to move arm 51 so as to apply pressure to the shaft 8 and stop its rotation. The arm 51 may be provided with a spring 53 if desired to cause a gradual application of the brake. The brake is automatically released by gravity when the member 2 is lowered. The

member 2 has another engaging part 54 which engages a stop piece 55 at the top of the casing of the jack so as to prevent the movable member 2 from being moved entirely outside of the casing.

In Figs. 13 and 14, I have illustrated a jack having a straight front so that it can be placed directly against a wall or an obstruction in order that the lower engaging 10 part would project under the wall or obstruction so as to engage it.

It will be noted (see Figs. 1, 2 and 6) that the casing 1 is provided with two interior partitions between which the lifting 15 member 2 is received, that these interior partitions divide the casing, as it were, into three chambers, a central chamber containing the lifting member, and two side chambers containing the two sections of the train 20 of gears, one section being in one chamber and the other section being in the other chamber, the shafts upon which the gears are mounted being supported at one end by these partitions and at the other end by the 25 outer walls of the casing.

I claim:

1. A portable jack comprising a suitable casing, a movable member mounted in said casing, a train of gears connected at one 30 end with said movable member so as to move it with relation to the casing when operated, means for connecting a motor to said train of gears at different points therealong, and means for disconnecting the gears intermediate the connecting points of the motor.

2. A portable jack comprising a suitable casing, two interior partitions dividing said casing into three chambers, a central chamber and two side chambers, a movable member 40 mounted in said casing between said partitions and having teeth on opposite faces thereof, two toothed wheels engaging the teeth on said movable member, said wheels operatively connected together, a train of gears connected with one of said toothed wheels, said train of gears divided into two sections, one section contained in one of said side chambers, and the other section contained in the other side chamber, an operating shaft at the end of said train of gears projecting from said casing.

3. The combination with a casing, of two interior partitions dividing said casing into three chambers, a central chamber and two side chambers, a movable member mounted in said casing between said partitions and having teeth on opposite faces thereof, two toothed wheels engaging the teeth on said movable member, said wheels operatively 55 connected together, a train of gears con-

nected with one of said toothed wheels, said train of gears divided into two sections, one section contained in one of said side chambers, and the other section contained in the other side chamber, shafts for said gears 65 supported at one end by the walls of the casing and at the other end by said partitions and an operating shaft at the end of said train of gears projecting from said casing, and means for applying a motor to said shaft so as to operate the jack and a supporting device associated with said casing for supporting the motor thereon.

4. A portable jack comprising a suitable casing, a movable member mounted in said 75 casing, a train of gears connected at one end with said movable member, a shaft at the other end of said train of gears arranged so that power may be applied thereto to drive the gears and move said movable member 80 and a retarding fan connected with said train of gears and adapted to retard the movement thereof as the movable member is moved toward its initial position.

5. A portable jack comprising a suitable 85 casing, a movable member mounted in said casing, a driving shaft operatively connected with said movable member and a brake device for said shaft directly actuated by said movable member when it reaches a predetermined position.

6. A portable jack comprising a suitable casing, a movable member mounted in said casing, a train of gears connected with said movable member, a driving shaft connected 95 with said train of gears so as to operate the same, a brake device associated with said driving shaft comprising an arm adapted to be directly engaged by a part on said movable member and a friction part connected with said arm and adapted to frictionally engage the part associated with said shaft whereby the power applied to the movable part is used to set the brake.

7. A portable shaft comprising a casing, 105 a movable member mounted in said casing, a train of gears connected with said movable member, fan blades within said casing and connected with a rotating part connected with said train of gearing, said fan 110 blades acting to resist the backward movement of the gears in said train.

In testimony whereof, I affix my signature in the presence of two witnesses this 26th day of October.

JAMES H. SHEAHAN.
